Primary Examiner—Antoine Duval Davis
Attorney, Agent, or Firm—Mathew R. P. Perrone, Jr.[57] **CLAIM**

The ornamental design for a left handed rear grip torchfoot, as shown and described.

DESCRIPTION

FIG. 1 is a front left perspective view of a left handed, rear grip torchfoot showing my new design;

FIG. 2 is a right side elevational view thereof, the broken line showing of a cutting torch being for illustrative purposes only and forming no part of the claimed design;

FIG. 3 is a rear elevational view thereof;

FIG. 4 is a front elevational view thereof;

FIG. 5 is a top plan view thereof; and,

FIG. 6 is a bottom plan view elevational view thereof.
